(57) **CLAIM**

The ornamental design for handle for a portable gaming monitor, as shown and described.

DESCRIPTION

FIG. 1 is a front-top-right perspective view of a first representative embodiment of a handle for a portable gaming monitor according to my new design;

FIG. 2 is a rear-bottom-left perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side elevational view thereof;

FIG. 8 is a right-side elevational view thereof;

FIG. 9 is a front-top-right perspective view of a second representative embodiment of a handle for a portable gaming monitor according to my new design;

FIG. 10 is a rear-bottom-left perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a left-side elevational view thereof; and,

FIG. 16 is a right-side elevational view thereof.

Embodiment 3 is a mirror image of Embodiment 1, shown in FIGS. 1-8.

Embodiment 4 is a mirror image of Embodiment 2, shown in FIGS. 9-16.

The dashed broken lines in the drawings show portions of the handle for a portable gaming monitor that form no part of the claimed design.

1 Claim, 14 Drawing Sheets
